Inventor:

Simon Smith

United States Patent Office.

SIMON SMITH, OF CLARKSBURG, NEW YORK.

Letters Patent No. 97,976, dated December 14, 1869.

IMPROVEMENT IN CHURNS.

The Schedule referred to in these Letters Patent and making part of the same.

To all whom it may concern:

Be it known that I, SIMON SMITH, of Clarksburg, in the county of Erie, in the State of New York, have invented a new Twin-Dasher Churn, for converting cream into butter. I do hereby declare that the following is a full, clear, and exact description thereof, reference being had to the accompanying drawing, and to the letters of reference marked thereon.

My invention consists in a churn of two dashers.

The body A, as shown in the accompanying drawing, is made of wood or metal, of oblong shape, and longer at the top than at the bottom.

The cover B is made in two parts. A joint in the middle sits in at the top, with a shoulder on the inside of the body, to hold the cover from settling into the churn; also, to keep the cream from escaping.

The cover is held to its place by two posts, C, with a shoulder on each, that bears on the covers.

The posts are supported by two loops, D.

The dashers E are suspended from each end of a walking beam, F, which is supported by two gudgeons, that pass through the top of the posts C.

Each dasher is made in two parts, with a joint a

little above the cover of the churn. The part from the joint downward is made of metal, and hollow, for the purpose of admitting cold or hot water, to give the cream the required temperature for churning.

The posts are movable, and a pin holds the two parts of the dashers together; and by extracting the pin, the posts, walking beam, and upper parts of the dashers, as well as the cover and lower parts of the dashers, are dispensed with.

The churn is worked by hand or machinery; if by hand, by taking hold of the end of the walking beam, and bearing down and up alternately; if by machinery, by attaching a pitman to the walking beam.

What I claim as my invention, and desire to secure by Letters Patent, is—

The combination of the hollow dashers E E, standard C, lever F, and churn-body A, all constructed and arranged as described.

SIMON SMITH.
